[57] CLAIM

The ornamental design for a doormat support plate or similar article, as shown and described.

DESCRIPTION

FIG. 1 is a top perspective view of a doormat support plate or similar article showing our new design;

FIG. 2 is a top plan view on a smaller scale;

FIG. 3 is a front elevational view thereof, the rear being a mirror image thereof;

FIG. 4 is a bottom plan view thereof;

FIG. 5 is a side elevational view thereof;

FIG. 6 is a fragmentary top plan view on a larger scale;

FIG. 7 is a fragmentary bottom plan view on the same scale as FIG. 6;

FIG. 8 is a fragmentary sectional view on the same scale as FIG. 6 taken along line 8—8 in FIG. 2; and

FIG. 9 is a view similar to FIG. 8 taken along line 9—9 in FIG. 2.
